UNITED STATES PATENT OFFICE.

JOHN B. HOWE AND FREDERICK D. FRY, OF DANBURY, CONNECTICUT, AS-SIGNORS, BY DIRECT AND MESNE ASSIGNMENTS, TO SAID FRY AND VERGIL E. BARNUM, OF SAME PLACE.

HAT-BLOCK.

SPECIFICATION forming part of Letters Patent No. 357,996, dated February 15, 1887.

Application filed June 21, 1886. Serial No. 203,794. (No model.)

To all whom it may concern:

Be it known that we, JOHN B. HOWE and FREDERICK D. FRY, citizens of the United States, residing at Danbury, in the county of 5 Fairfield and State of Connecticut, have invented certain new and useful Improvements in Hat-Blocks; and we do hereby declare that the following is a full, clear, and exact description of the same, reference being had to the annexed drawings, making a part of this 10 specification, and to the letters and figures of reference marked thereon.

Figure 1 of the drawings is a perspective view of the under side of a hat-block with 15 our improved fastening devices applied thereto and the hat in position over the block; Fig. 2, a vertical section in detail on line y y of Fig. 1; Fig. 3, a horizontal section thereof, and Fig. 4 detail views in perspective of the 20 several parts of the fastening device.

The present invention has for its object to provide a simple and effective means for securing hats to their blocks while being finished, thereby dispensing with the usual 25 tacks, cords, and other like fastenings now in common use; and the invention consists in the peculiar construction of the fastening and means for operating it, substantially as shown in the drawings, and hereinafter described and claimed.

In the accompanying drawings, A represents a hat-block of any of the usual forms, and B represents the hat held thereon while being finished by our improved fastening device, which is a permanent fixture to the 35 block and consists of a pin or spur, C, bent as shown in Fig. 4, which we shall hereinafter term a "crank-pin." The shank of this pin enters a perforation in a circular block, D, 40 said block being seated in a socket-plate, E, fitting in a mortise in the under side of the block A. The block D is held within the socket of the plate E by means of a screw, a, which forms the pivotal axis of the block D. 45 The screw a passes through a perforation in a brace, b, which extends diametrically across the block D, and has its ends seated in recesses c in the plate E. The block D is cut away, as shown at d, to form a space for the 50 pin to work in, said pin C extending through a perforation, e, in the side of the plate E.

The block D is provided with perforations diametrically opposite each other, as shown in Fig. 1, for engaging therewith a suitable key or tool for turning it.

When the block D is turned in the proper direction, as indicated by the arrow, Fig. 3, the pin will be drawn in, as shown in dotted lines, and when the block is turned in the opposite direction the pin is forced out and 60 through the hat B and brought down tightly against it, which motion of the pin is attained by its peculiar bend, thus holding the body of the hat to the block A and preventing it from slipping or working off the block A.

It is evident that other means may be employed for operating the crank-pin C besides those shown, and we therefore reserve the right to make such changes or modifications in the operating mechanism as come within 7c the scope of our invention, the essential feature of which is the crank-pin adapted to pass through the body of the hat and afterward turn down against it, as hereinbefore described.

Having now fully described our invention, what we claim as new, and desire to secure by Letters Patent, is—

1. A fastening device for securing hats on hat-blocks, consisting of a movable crank-pin 80 adapted to pass through the hat and afterward turn down against it, substantially as and for the purpose set forth.

2. A device for securing hats on hat-blocks, consisting of a crank-pin and means for operating it, consisting of a block, movable upon a pivot, said pin entering a perforation in said block, substantially as and for the purpose set forth.

3. In the means for securing hats to hat-blocks, the combination of a crank-pin, a circular block for operating the same, a socket-plate to form a seat for the block, and a screw for connecting the block to the plate, substantially as and for the purpose set forth.

In testimony that we claim the above we have hereunto subscribed our names in the presence of two witnesses.

JOHN B. HOWE.

Witnesses: FREDERICK D. FRY.

LEVI K. WILDMAN,
FREDK. B. CROFUTT.
